PRESSURE RELEASE FOR WRINGERS

Charles B. Williams, Shaker Heights, Ohio, assignor to Williams Industries, Inc., Cleveland, Ohio, a corporation of Ohio

Application September 10, 1931
Serial No. 562,111

24 Claims. (Cl. 68—32)

This invention relates to a pressure release for a wringer, and especially to a pressure release arranged to be used in a wringer having a pair of pressure rolls and an auxiliary roll, resiliently retained in contact with one of the pressure rolls, wherein the material is fed by the operator between the auxiliary roll and an associated pressure roll, and then passes between the two pressure rolls, which coact to squeeze the moisture from the material.

The general object of this invention is to provide a release mechanism which will act to relieve the pressure between, and separate a pair of wringer rolls, which are normally resiliently retained in contact with each other.

A further object is to provide a manually operated release mechanism, which is especially arranged for use in connection with a wringer, having a pair of coacting pressure rolls, and an auxiliary roll normally arranged to be resiliently retained in contact with one of the pressure rolls, and which release mechanism will relieve the pressure between the auxiliary roll and its associated pressure roll and entirely separate such rolls.

Other objects of this invention will become more apparent from the following description, referring to a preferred embodiment thereof, illustrated in the drawings. The essential and novel characteristics of the invention will be set forth in the claims.

Referring again to the drawings, wherein I illustrate a preferred form of my invention, Fig. 1 is a substantially centrally located vertical section, and is indicated by the lines 1—1 on Fig. 2; Fig. 2 is a side elevation of a wringer, embodying my invention; Figs. 3 and 4 are vertical transverse sections, as indicated by the lines 3—3 on Fig. 1; Fig. 4 is a section taken in substantially the same plane as Fig. 3, but illustrating some of the parts in a different position; Fig. 5 is a side elevation of a modified form of my invention, illustrated in connection with a wringer, having a slightly different construction than that shown in Figs. 1 to 4, inclusive; Fig. 6 is a vertical transverse section, as indicated by the lines 6—6 on Fig. 5; Figs. 7 and 8 are sections, taken in substantially the same plane as Fig. 6, but illustrating some of the parts in different positions; Fig. 9 is a fragmentary transverse vertical section, as indicated by the lines 9—9 on Fig. 5; Fig. 10 is a fragmentary vertical section, as indicated by the lines 10—10 on Fig. 6, Figure 11 is a sectional detail of Figure 10.

Referring again to the drawings, and especially

to Figs. 1 to 4, inclusive, I illustrate one form of my invention in connection with a wringer, which is provided with a pair of auxiliary rolls arranged to coact with a pair of contacting pressure rolls respectively. The arrangement of my release mechanism is such that it will operate to separate the auxiliary rolls from their respective pressure rolls.

The wringer, as shown in Fig. 1, comprises a pair of substantially vertically extending hollow side frame members 10 and 11, joined together by suitable cross frame members 12. Mounted in a substantially horizontal plane between the frame members 11 and 12 are a pair of shafts 14 and 15, on which are rigidly secured pressure rolls, 16 and 17, respectively. The shafts 14 and 15 are rotatably mounted in suitable bearing blocks 18, carried by the frame members 11 and 12. One of the bearing blocks 18 in each frame member 11 or 12 abuts a stationary block or bar 19 of the frame member, the other bearing members 18 being spaced apart from frame members 20, carried by respective end frames 11 and 12. Between the latter bearing members 18 and the frame members 20 are compression springs 21, arranged to normally urge the roll 17 into contact with the roll 16. The pressure between the rolls 16 and 17 is adjusted by suitable adjusting screws 22, mounted in a threaded engagement with respective frame members 20 and arranged to coact with one end of respective compression springs 21. Immediately below the pressure rolls 16 and 17 are a pair of auxiliary rolls 30 and 31, which contact with each other and with the pressure rolls, respectively. The end portions of the shafts 32 and 33 which support the auxiliary rolls 30 and 31 are carried in a bearing block 34, which is slidably mounted in the frame members 10 and 11, there being one such bearing block 34 in each of the frame members 10 and 11.

The auxiliary rolls 30 and 31 are normally retained in contact with their respective pressure rolls by a spring 35, which operates to resiliently maintain the contact between each auxiliary roll 30 and 31, and their respective pressure rolls 16 and 17. One end of each spring 35 is secured, as at 36, to its respective bearing block 34, and the other ends are secured to one end of respective links 38, each of which is pivoted as at 39, to rotatable disc 40 and 41, respectively. It will be noted that the pivot 39 is eccentrically located on the discs 40 and 41. Hence, the rotation of the discs will lower the pivots 39, and cause the tension on the springs 35 to be re-

leased and separate the auxiliary rolls 30 and 31 from their respective pressure rolls 16 and 17.

To enable the operator to readily rotate the discs 40 and 41, each disc is provided with an operating handle 42. The construction is such that the rotation of either disc 40 or 41 will serve to rotate the other disc and therefore lower both bearing blocks 34 simultaneously. To this end the discs 40 and 41 are rigidly secured 5 to a cross shaft 43, mounted in openings 44 in plates 45, which are secured to the inner faces of the frame members 10 and 11. Hence, the operator may grasp either one of the handles 42 and conveniently separate the rolls, thereby preventing injury to the garment or to the fingers, 10 which might be caught between an auxiliary roll and a pressure roll when material of abnormal thickness is passed therebetween.

I prefer to arrange the construction so that 20 the reaction of the springs 35 is transmitted directly from the discs 40 and 41 to the top of the frame members 10 and 11. To this end I mount a substantially flat bar 46 on the top surface 47 of each frame member 10 and 11, and so arrange the bars that the lowermost surfaces of its respective discs 40 or 41 will bear thereon.

I have shown the wringer as being operated by a suitable manually operated handle 48, but I contemplate that it may be operated by a suitable power device if desired. I prefer to drive one pressure roll by the operating means and drive the other pressure roll frictionally from the first pressure roll. As shown in the drawings, I have mounted the handle 48 on the shaft 15, thereby 30 positively driving the pressure roll 17. The pressure roll 18 is frictionally driven by its contact with the pressure roll 16. The auxiliary rolls 30 and 31 are likewise normally driven, by reason of their contact with their respective pressure rolls 16 and 17. However, I prefer to provide the auxiliary roll shafts 32 and 33 with spur gears or 40 pinions 49, arranged to mesh with each other. When garments are fed between one pressure roll and its associated auxiliary roll, the other auxiliary roll will remain in contact with its associated pressure roll, and will be frictionally driven therefrom, while the gears 49 will serve to positively drive the first-named auxiliary roll.

In Figs. 5 to 10 inclusive I show my release mounted on a modified form of wringer. In this instance, the pressure rolls 16 and 17 and the auxiliary rolls 30 and 31 are mounted in a flanged drum 60. The flanges 61 of which are embraced by annular flanges 62 of a second pair of drums 63. The drums 63 are spaced apart, and are rigidly secured to suitable cross frame members 64, which form a base for the wringer. This construction is such that when the inner drum 60 is rotated relative to the outer drum 63, the auxiliary roll 30 and its associated pressure roll 16 are tilted slightly clockwise from a vertical position, thereby positioning these rolls so that an operator may conveniently feed the garments in the direction of the arrow in Fig. 6, and enabling the operator to readily see the garments as they pass into the bite of the rolls 30 and 16. However, when garments are fed from the opposite side of the wringer, namely, from 60 the right hand side, referring to Figs. 6 to 8, inclusive, the auxiliary rolls and the inner drum 60 will be rotated in a counter-clockwise direction relative to the outer drum 63, thereby tilting the pressure roll 17 and auxiliary roll 31 to the 75 position indicated in Fig. 8. In this position

the pressure roll 17 and its associated auxiliary roll 31 have been tilted in a counter-clockwise direction, so that the garments may be fed from the right hand side of the wringer in the direction of the arrow, as indicated in Fig. 8.

To retain the rolls in either of the adjusted positions, shown in Figs. 6 and 8, I prefer to provide a spring-pressed latch 70, which is preferably carried by one of the inner drums 60, and arranged to engage notches 71 in the corresponding outer drum 63. This latch 70 comprises a lever 72, pivoted at 73 to the inner drum 60, and normally retained in engagement with one of the notches 71 by a suitable spring 74.

My modified form of release comprises a pair 90 of tension springs 35a, one end of each of which supports an auxiliary roll bearing 34, and the other end of each of which is secured to respective cables 75, rigidly secured to a drum-like extension 76, of a shaft 77, journaled in the inner drum members 60.

Rigidly secured to the shaft 77, adjacent the drum-like portions 76, are spur gears 79, which are arranged to mesh with suitable segmental racks 80 respectively. The racks 80 are secured 100 to the flange 62 of the outer or stationary drum 63. The arrangement is such that when the pressure rolls 16 and 17 are in a substantially horizontal position, as shown in Fig. 7, the cable 75 is extended its fullest amount. However, as 105 the inner drum 60 is rotated to one side or the other, to the position shown in Figs. 6 or 8, the gears 79 will be rotated, due to the relative travel between them and their respective segmental racks 80, thereby rotating the drums 76 and 110 winding the cable 75 thereabout. This is so arranged as to bring the auxiliary rolls 30 and 31 into contact with their respective pressure rolls, and simultaneously place the spring 35a under sufficient tension to permit the feeding of the 115 garments between the auxiliary rolls 30 and 31, and their respective pressure rolls.

Assuming that the wringer rolls are in the position shown in Fig. 6, the operation of the receiving mechanism is as follows: The operator 120 depresses the release lever 70, and causes it to disengage the notch 71 in the drum 63, a tension spring 90, one end of which is secured to a stud 91, carried by the frame drum 60, the other end of which is secured to a stud 92, carried by the 125 frame drum 63, then acts to cause relative rotation between the two drums. The pinions 79 then travel along the racks 80, causing the cables 75 to be unwound, thereby releasing the tension of the spring 35a, and permitting the bearing 130 members 34 and their respective auxiliary rolls 30 and 31 to drop clear of the pressure rolls to the positions shown in Fig. 7.

When it is desired to cause the auxiliary rolls 30 and 31 to contact with their respective pressure rolls 16 and 17, the latch 70 is again depressed and the operator, by means of the latch, 135 positively rotates the inner drum 60 relative to the outer drum 63, the action of the gears 79 on racks 80, then cause the cables 75 to be wound 140 around their respective drums 76, thereby again drawing the pressure rolls and their respective supplementary rolls 30 and 31 into contact with each other, and placing sufficient tension upon the spring members 35a to permit the respective 145 coacting pressure and auxiliary rolls to feed material into the bite of the two pressure rolls.

From the foregoing description it will be readily seen that I have provided an efficient pressure release mechanism, which is especially adapted 150

for use in connection with a wringer having a pair of pressure rolls and a pair of supplementary rolls coacting with the pressure rolls respectively, which release mechanism will relieve the pressure between the auxiliary rolls and their respective pressure rolls and cause a separation therebetween.

I claim:

1. In a wringer, the combination of a pair of pressure rolls, a pair of auxiliary rolls, resilient means to maintain both auxiliary rolls simultaneously in contact with respective pressure rolls, and manually operable means to cause a separation between the auxiliary rolls and their respective pressure roll.

2. In a wringer, a pair of pressure rolls, resilient means adapted to retain the pressure rolls in contact with each other, a pair of auxiliary rolls arranged to contact with respective pressure rolls, a second resilient means adapted to normally retain both of said auxiliary rolls simultaneously in contact with their respective pressure rolls, and means to cause a separation between the pressure rolls and their coacting auxiliary rolls, and release the pressure on said last-named resilient means.

3. In a wringer, the combination of a pair of pressure rolls, a pair of auxiliary rolls contacting with the pressure rolls respectively, a pair of rigid bearing members supporting the auxiliary rolls at their ends, resilient means to support said bearing member, and a manually operable means to permit the bearing members to drop and thereby cause a separation between the auxiliary rolls and the pressure rolls.

4. In a wringer, the combination of a pair of pressure rolls, a pair of auxiliary rolls contacting with the pressure rolls respectively, a pair of rigid bearing members supporting the auxiliary rolls at their ends, resilient means to support said bearing members, a manually operable means to permit the bearing members to drop in the frame, and wherein said manually operable means is arranged to cause both auxiliary rolls to simultaneously separate from their respective pressure rolls.

5. In a wringer, the combination with a frame, of a pair of pressure rolls mounted in the frame, a pair of auxiliary rolls inserted in the frame and arranged to contact with the pressure rolls respectively, a pair of rigid bearing members supporting the auxiliary rolls at their ends, resilient means secured adjacent the top of the frame and arranged to suspendingly support said bearing members, and a manually operable means operatively connected to said resilient means and the frame to cause the bearing members to drop in the frame and thereby separate the auxiliary rolls from the pressure rolls.

6. In a wringer, the combination with a frame, of a pair of pressure rolls, a pair of auxiliary rolls adapted to coact with respective pressure rolls, wherein the work is first fed between one of said pressure rolls and its respective auxiliary roll and then between the bite of the two pressure rolls, a mounting for said auxiliary rolls, means including a resilient member arranged to support said mounting in the frame and maintain both of said auxiliary rolls simultaneously in contact with their respective pressure rolls, and a manually operable lever acting on said last-named means to cause said resilient means to become inactive.

7. In a wringer, the combination with a frame, of a pair of pressure rolls, an auxiliary roll adapt-

ed to coact with one of said pressure rolls, wherein the work is first fed between the pressure roll and the auxiliary roll and then between the bite of the two pressure rolls, a mounting for said auxiliary roll, means including a resilient member arranged to suspend said mounting in the frame, and a manually rockable member arranged to raise and lower the resilient member at the will of the operator.

8. In a wringer, the combination with a frame, of a pair of pressure rolls, an auxiliary roll adapted to coact with one of said pressure rolls, wherein the work is first fed between the pressure roll and the auxiliary roll and then between the bite of the two pressure rolls, a mounting for said auxiliary roll, a manually rotatable member mounted in said frame, means including a resilient member arranged to support said mounting in the frame, and wherein one end of said auxiliary member is eccentrically secured to said rotatable member and the other end is secured to said mounting, whereby the movement of said rotary member will cause the auxiliary roll to be separated from the pressure roll.

9. In a wringer, a main frame, a supplemental frame moveably mounted in the main frame, a pair of pressure rolls mounted in the supplemental frame, an auxiliary roll mounted in the supplemental frame and adapted to contact with one of the pressure rolls, resilient means to maintain the auxiliary roll in contact with the pressure roll, and means operative by the relative movement between the main frame and the supplemental frame to cause a separation between the auxiliary roll and its respective pressure roll.

10. In a wringer, a main frame, a supplemental frame moveably mounted in the main frame, a pair of pressure rolls mounted in the supplemental frame, an auxiliary roll carried by one of said frames and adapted to contact with one of the pressure rolls, resilient means arranged to suspendingly support the auxiliary roll and maintain it in contact with the pressure roll, and means operative by the relative movement between the main frame and the supplemental frame to cause the auxiliary roll to be raised and lowered as desired.

11. In a wringer, a main frame, a supplemental frame rotatably mounted in the main frame, a pair of pressure rolls carried by the supplemental frame, resilient means adapted to retain the pressure rolls in contact with each other, an auxiliary roll carried by the supplemental frame and arranged to contact with one of the pressure rolls, a second resilient means adapted to normally retain said auxiliary roll in contact with one of the pressure rolls, and means acting consequent upon relative movement between the main frame and the supplemental frame to separate the auxiliary roll from the pressure rolls.

12. In a wringer, a main frame, a supplemental frame rotatably mounted in the main frame, a pair of pressure rolls mounted in one of said frames, a pair of auxiliary rolls mounted in one of said frames and contacting with the pressure rolls respectively, a pair of bearing members supporting the auxiliary rolls at their ends, resilient means to support said bearing members, and means acting consequent upon relative rotation between the main frame and the supplemental frame to cause the bearing members to drop in the frames and cause a separation between the auxiliary rolls and the pressure rolls.

13. In a wringer, the combination with a main frame, of a supplemental frame rotatably mounted

- in the main frame, of a pair of pressure rolls mounted in one of said frames, an auxiliary roll mounted in one of said frames and adapted to coact with one of said pressure rolls, and means whereby relative movement between the main frame and the supplemental frame will separate the auxiliary roll from the pressure rolls.
14. In a wringer, a main frame, a supplemental frame rotatably mounted in the main frame and having its axis of rotation coinciding with the axis of the main frame, a pair of pressure rolls mounted in the supplemental frame, the axis of one of said pressure rolls coinciding with the axis of said frames, an auxiliary roll carried by the supplemental frame, resilient means to maintain the auxiliary roll in contact with the axially mounted pressure roll, and means acting consequent upon relative rotation between the main frame and the supplemental frame to cause a separation between the auxiliary roll and the axially mounted pressure roll.
15. In a wringer, the combination with a main frame of a supplemental frame rotatably mounted in the main frame, of a pair of pressure rolls mounted in one of said frames, an auxiliary roll mounted in one of said frames and adapted to coact with one of said pressure rolls, a segmental rack secured to one of said frames and a pinion secured to the other of said frames, and means whereby relative movement between the main frame and the supplemental frame will separate the auxiliary roll from the pressure rolls.
16. In a wringer, a main frame, a supplemental frame rotatably mounted in the main frame, a pair of pressure rolls in one of said frames, a pair of auxiliary rolls mounted in one of said frames and contacting with the pressure rolls respectively, a pair of bearing members supporting the auxiliary rolls at their ends, resilient means having one end thereof secured to said bearing members, a flexible member secured to the other end of said resilient member, a drum mounted in one of said frames and to which said flexible member is secured, and means acting consequent upon relative movement between the main frame and the supplemental frame to rotate said drum and wind the flexible member thereon.
17. In a wringer, the combination of a frame, a pair of pressure rolls, a pair of auxiliary rolls, a pair of end members movably mounted in the frame and arranged to support said auxiliary rolls, and a pair of springs mounted in said frame and arranged to support respective end members between the axes of the auxiliary rolls.
18. In a wringer, the combination of a stationary frame having a pair of upright end members spaced apart, a supplemental frame mounted between the upright member and pivotally carried thereby to turn on an axis connecting such end members, a pressure roll and a pair of auxiliary rolls carried by said last-mentioned frame and adapted to occupy various axial positions while preserving their relation one to the other, and a second pressure roll adapted to coact with the first pressure roll.
19. In a wringer, the combination of a stationary frame having a base portion and a pair of upright members spaced apart, a frame mounted between the upright end members and pivotally carried thereby to turn on an axis connecting said end members, a pressure roll and a pair of auxiliary rolls carried by said last-mentioned frame and adapted to occupy various actual positions while preserving their relations one to the other, a second pressure roll, means for causing pressure between the second-named pressure roll and the first-named pressure roll, and means for locking the last-mentioned frame in a plurality of positions relative to the first-mentioned frame.
20. In a wringer, a frame, a pair of pressure rolls rotatably mounted in a horizontal plane in the frame and adapted to squeeze the liquid from the work, a pair of auxiliary rolls, rotatably mounted in the frame in alignment with and substantially beneath respective pressure rolls, each of said auxiliary rolls being of substantially the same length as the pressure rolls, yielding means to retain the last-named rolls in contact with the pressure rolls respectively, each auxiliary roll coacting with its respective pressure roll to feed material from the bite of such auxiliary roll and pressure roll into the bite of the two pressure rolls, and wherein the material fed between either pressure roll and its associated auxiliary is gripped and squeezed between two pressure rolls without reversing the direction of rotation of said pressure rolls.
21. In a wringer, a frame, a pair of pressure rolls mounted in a substantially horizontal plane 100 to said frame, a pair of auxiliary rolls disposed beneath and normally in contact with respective pressure rolls, the axis of each auxiliary roll being in a substantially vertical plane passing through the axis of the respective pressure roll, 105 said auxiliary rolls adapted to contact with their respective pressure rolls substantially throughout the entire length of the pressure rolls, means to rotate the pressure rolls, and wherein the work passes first between either auxiliary roll and its 110 associated pressure roll and then between the two pressure rolls and is ejected from substantially the top of the wringer without reversing the direction of rotation of any of said rolls.
22. In a wringer, a frame, a pair of pressure 115 rolls rotatably mounted in a horizontal plane in the frame and adapted to squeeze the liquid from the work, a pair of auxiliary rolls, rotatably mounted in the frame in alignment with and substantially beneath respective pressure rolls, 120 each of said auxiliary rolls being of substantially the same length as the pressure rolls, said auxiliary rolls being substantially the same diameter and length as their respective pressure rolls, yielding means to retain the last-named rolls 125 in contact with the pressure rolls respectively, each auxiliary roll coacting with its respective pressure roll to feed material from the bite of such auxiliary roll and pressure roll into the bite of the two pressure rolls, and wherein the material fed between either pressure roll and its associated auxiliary is gripped and squeezed between two pressure rolls without reversing the direction of rotation of said pressure rolls.
23. In a wringer, a frame, a pair of pressure 135 rolls rotatably mounted in said frame and having an upwardly extending bite, means to rotate one of said rolls, resilient means urging one of said rolls into contact with the other whereby both of said rolls are driven, one roll being frictionally 140 driven through the other, a pair of supplemental rolls resiliently retained in contact with respective pressure rolls, resilient means to lightly press the auxiliary rolls into contact with their respective pressure rolls, whereby work passes first 145 between either auxiliary roll and its respective pressure roll and then between the two pressure rolls, and means independent of the auxiliary roll surfaces to drive one auxiliary roll from the other auxiliary roll, whereby when material passes be- 150

tween one auxiliary roll and its associated pressure roll said auxiliary roll will be driven independently of the contact between said auxiliary roll and its associated pressure roll or the material gripped therebetween.

24. In a wringer, the combination of a pair of pressure rolls, a pair of auxiliary rolls contacting with and lying substantially beneath respective pressure rolls, a pair of rigid bearing blocks supporting said rolls at their ends, resilient means

for supporting the bearing blocks, and guides for said bearing blocks whereby the auxiliary rolls may be moved as a unit without disturbing their relationship one to another and whereby one auxiliary roll may be separated from its respective pressure roll without disturbing the contact between the other auxiliary roll and its associated pressure roll and without disturbing the relationship between the two auxiliary rolls.
